United States Patent Office.

JOHN H. MARTIN, OF SALEM, NEW YORK.

Design No. 4,185, dated June 28, 1870.

DESIGN FOR A SASH-HOLDER.

The Schedule referred to in these Letters Patent and making part of the same

I, JOHN H. MARTIN, of the town of Salem, in the county of Washington, State of New York, have invented and produced a new and original Design for Window-sash Holders or Fasteners, of which the following is a specification.

The nature of my said design is fully represented in and by the accompanying drawing or photographic illustration, to which reference is hereby made, and which is made a part of this my specification.

I claim as my invention—

The design for a window-sash fastener and sup-

porter, as shown, to wit: with a flange surrounding it, two notches at opposite ends and sides, and a diagonal slot within the same.

In testimony whereof I have, on this 10th day of June, 1870, hereto set my hand in presence of two witnesses, to wit:

JOHN H. MARTIN.
